PROSTATE GLAND MASSAGER

Emmett W. Johnson, Hot Springs, Ark.

Application May 29, 1957, Serial No. 662,476

6 Claims. (Cl. 128—24.2)

This invention relates to the care and treatment of the human body and more particularly to the treatment of various parts of the body therapeutically and otherwise and specifically to a therapeutic device for the treatment of the prostate gland and associated parts.

It is well known that the prostate gland sometimes becomes acutely inflamed or enlarged, and requires attention and sometimes removal. Treatment of this and other glands of the body have been found to be of help and the present invention is concerned with such treatment and the equipment employed.

It is an object of the invention to provide a relatively simple and inexpensive device for massaging the prostate gland and seminal vesicle, which may be used in the privacy of the home without the aid of a doctor or a nurse to thereby improve the health and wellbeing of the individual.

Another object of the invention is to provide a therapeutic device of the character indicated in which a certain amount of heat can be applied during massaging treatment of the prostate gland and similar parts of the human body.

A further object of the invention is to provide a kit including a case or container including a motor, a flexible cable, and a generally cylindrical massager having a spiral rib for contact with the gland or glands to be massaged, as well as an electrical heating element, a time clock, and other appropriate mechanism.

Other objects and advantages of the invention will be apparent from the following description taken in conjunction with the accompanying drawing wherein:

Fig. 1 is a perspective of a prostate gland massaging kit;

Fig. 2, a section on the line of 2—2 of Fig. 1;

Fig. 3, a side elevation of the massaging element per se;

Fig. 4, a transverse section on the line 4—4;

Fig. 5, a wiring diagram; and,

Fig. 6, a section of the flexible cable and plug.

Briefly stated the invention is a kit for the massaging of the prostate gland and the small seminal vesicles and includes a relatively hard generally cylindrical member with a bulbous end and a spiral rib extruding along said member therefrom to a flared skirt at the opposite end of said member for limiting insertion thereof, said member being driven through a flexible cable from an electric motor in order to stimulate the flow of fresh blood through the tissues to restore normalcy and to eliminate various undesirable conditions such as infection and the like.

With continued reference to the drawings the device of the present invention comprises a generally cylindrical body 10 having a slightly enlarged rounded or bulbous head 11 at one end and a tapered or frusto-conical skirt 12 at its opposite end for limiting the insertion of the device. Between the head and skirt is a spiral rib 13 such rib being provided for the application of force as it rotates. The device is intended to be both heated and

2

rotated with the heat supplied by a coil 14 through a pair of terminals 15 mounted in the rear plate 16 of the skirt 12 of the device and such terminals being adapted to be inserted in an electrical socket 17 connected with a source 5 of energy such as an electric socket not shown by a cord 18 and a plug 19.

The body 30 is adapted to be mechanically rotated to produce the massaging action and in order to accomplish this result a socket 20 is provided in which the terminals 10 15 are adapted to be received, such socket having a polygonal opening 21 for reception of the complementary polygonal end 22 of a flexible cable 23 detachably received within the coupling 24 connected to a shaft 25 which extends into a gear reduction box 26 coupled to a motor 27 in a manner to drive the shaft 25 through such gear reduction. The flexible cable 23 is mounted in a flexible housing 28 detachably secured in place by threaded couplings 29 and 30 to the gear reduction box 26 and the rear portion of the handle or holder 33 in 20 which the member 20 is rotatably mounted. The member 20 is retained in the holder 33 by means of a tension spring 34 in the form of a snap ring. By the disconnection of the threaded coupling 29 the flexible cable and its housing may be detached from the gear reduction 25 mechanism 26.

The motor 27 and gear reduction mechanism 26 are contained within a casing or container 35 having a removable cover 36 and adapted to be carried by a handle 37 secured in closed position by a staple and hasp 38. The kit is composed of the container 35 with contained mechanism and the flexible cable 23 and its casing 28 and the massager 10 and associated structure.

The socket 17 is mounted on a channel 39 within the container 35 and said container is also provided with a pair of switches 40 and 41 for controlling the heating element 14 and the motor 27, respectively, a light 42 being in the circuit with the heating element to indicate its operation. A timing device 43 may also be provided to control the length of operation of the heating element.

40 The device is designed for the specific treatment of the prostate gland and is intended to massage the same and the small seminal vesicle by being rotated at a relatively low rate of speed as for example, 8 R. P. M. The rib on the device bears against the prostate gland causing the flow of fresh blood through the tissues in turn aiding it back to normal and the elimination of various infections or changes due to age thereby avoiding acute inflammation or enlargement requiring removal.

45 It will be obvious to those skilled in the art that various changes may be made in the invention without departing from the spirit and scope thereof and therefore the invention is not limited by that which is illustrated in the drawing and described in the specification, but only as indicated in the accompanying claims.

55 What is claimed is:

1. A therapeutic kit comprising a container, a plug for disposition in an electrical socket, conductors extending from said plug into said container, a motor and a resistance heater, an adjustable timer for said heater, reduction gearing connected to be driven by said motor, an elongated generally cylindrical rotary member having a bulbous end with a spiral massaging rib extending rearwardly therefrom and terminating in spaced relation to 60 its rear end, a flexible skirt about the rear end of said member for limiting the insertion thereof, a handle for holding said rotary member, a flexible cable connected to said rotary member for supplying electrical energy thereto for heating and driving the same and having one 65 end attached to said reduction gearing by a detachable connection whereby said cable and rotary member may 70

be readily transported in said container and readily removed and used.

2. A therapeutic kit comprising a container, a plug for disposition in an electrical socket, conductors extending from said plug into said container, a motor in said container connected to receive energy from said conductors, reduction gearing connected to be driven by said motor, an elongated generally cylindrical rotary member having a bulbous end with a spiral massaging rib extending rearwardly therefrom and terminating in spaced relation to its rear end, a flexible skirt about the rear end of said member for limiting the insertion thereof, a handle for holding said rotary member, a flexible cable connected to said rotary member for driving the same and having one end attached to said reduction gearing by a detachable connection whereby said cable and rotary member may be readily transported in said container and readily removed and used.

3. A therapeutic kit comprising a container, a plug for disposition in an electrical socket, conductors extending from said plug into said container, a motor in said container connected to receive energy from said conductors, reduction gearing connected to be driven by said motor, an elongated generally cylindrical rotary member, a handle for holding said rotary member, a flexible cable connected to said rotary member for driving the same and attached to the reduction gearing by a detachable connection whereby said cable and rotary member may be readily transported in said container and readily removed and used.

4. A kit for the massaging of the prostate gland comprising an elongated generally cylindrical rotary member

having a bulbous end and a spiral rib extending rearwardly therefrom and terminating in spaced relation to its rear end, a flexible skirt about the rear end of said member for limiting the insertion thereof, means for the application of heat to said member, a flexible cable connected to said member, a motor connected to said cable for rotating the same and said member, reduction gearing between said motor and said cable for causing reduction in the speed of said cable, and a handle by which said rotary member may be held during use.

5. A kit for the massaging of the prostate gland comprising a rotary member having a massaging rib, a flexible cable connected to said member for rotating the same, a motor for rotating said cable, reduction gearing between said motor and said cable to cause the rotation of said cable at a slow speed, electrical heating means for said rotary member and conductors for supplying electrical energy to said motor and said electrical heating means, and control means for the control of the latter.

10 6. A prostate gland massager comprising a generally cylindrical rotary member having a bulbous end portion, power means for slowly rotating said member, means for heating said member, and means by which said member may be held and manipulated while it is being slowly rotated.
